UNITED STATES PATENT OFFICE.

FERNANDO A. ROBINSON AND BENJAMIN F. ROBINSON, OF CLARKSBURG,
WEST VIRGINIA.

DESIGN FOR A SPOON.

SPECIFICATION forming part of Design No. 21,374, dated Mar. 1, 1892.

Application filed January 21, 1892. Serial No. 418,854. Term of patent 3½ years.

To all whom it may concern:

Be it known that we, FERNANDO A. ROBINSON and BENJAMIN F. ROBINSON, citizens of the United States, residing at Clarksburg, in the county of Harrison and State of West Virginia, have invented and produced a new and original Design for Spoons, of which the following is a specification, reference being had to the accompanying drawings, wherein—
Figure 1 is an obverse view of a spoon made according to our design, and Fig. 2 a reverse view thereof.

The leading feature of our design is the shape for a spoon, as herein shown, the same provided with an ornamentation consisting of a representation of the house wherein General "Stonewall" Jackson was born, placed within the bowl of the spoon, and upon the handle suitable floriated bordering figures.

The view of the Jackson homestead, which we select for illustration, is shown at A, Fig. 1, and the ornamentation upon the handle is clearly shown at B. We represent the house as viewed from the street, together with its immediate surroundings, the fence, gate, trees, &c.

In practice we may surround the inner edge of the bowl with a raised scallop; but we do not desire to limit ourselves thereto, as other forms of finish may be employed equally well.

What we claim is—

The design for a spoon, as herein shown and described.

FERNANDO A. ROBINSON.
BENJAMIN F. ROBINSON.
